(57) **CLAIM**

The ornamental design for a sliding lid closure, as shown and described.

DESCRIPTION

FIG. 1 is a perspective view of a sliding lid closure showing our new design, with the sliding lid closure in the open position;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and

FIG. 8 is a perspective view thereof, with the sliding lid closure in the closed position; and,

FIG. 9 is a rear perspective view thereof, with the sliding lid closure in the closed position.

The broken lines showing a lid represent environmental structure. All other broken lines illustrate portions of the sliding lid closure. The broken lines form no part of the claimed design.
